HYDRAULIC VISE HAVING RESERVOIR,
PUMP, AND CYLINDER CARRIED BY
MOVABLE JAW

Julmer Helstrom, Cook, Minn.

Application June 8, 1950, Serial No. 166,827

1 Claim. (Cl. 81—17.2)

1

This invention relates to a vise, and has special reference to a vise having a hydraulically operated movable jaw.

One of the principal objects of the instant invention is to provide a hydraulically operated vise in which a movable hollow jaw constitutes a fluid reservoir and carries a manually operated hydraulic pump, and in which a hollow stem on said movable jaw constitutes a guide and a movable cylinder.

Another object is to provide a hydraulically operated movable vise jaw with air pressure operating means to facilitate the using of the vise.

These and other objects and advantages will become more apparent as the description of the invention proceeds.

In the accompanying drawings forming a part of this application:

Fig. 1 is a vertical sectional view of my vise through one of the operating pistons.

Fig. 2 is a vertical sectional view of a portion of the movable jaw of my vise showing the bleeder valve arrangement.

Fig. 3 is an end elevational view of my vise with parts broken away.

Fig. 4 is a sectional view on the line 4—4, Fig. 1.

In the drawing, the reference numeral 1 indicates the base portion of my vise which carries the fixed jaw 2, the latter having an opening 3 therethrough through which the stem 4 of the movable jaw 5 extends and is reciprocated.

As shown in the drawing, the movable jaw 5 is hollow as at 6 and serves as the reservoir for the hydraulic fluid 7 used for the operation of the vise, the jaw 5 having an inner wall 8, a bottom wall 9, and an outer wall 10 which curves inwardly to meet the inner wall at the working face of the jaw, as shown, and these walls form the hollow reservoir 6. An auxiliary wall 11 is mounted within the reservoir 6 and is spaced from the inner wall 8 to form a passage 12.

The outer wall 10 is preferably cut away as at 13 forming an opening into the reservoir to permit work to be done on the interior thereof, as on the auxiliary wall 11, and a plate 14 is preferably secured over the cut away portion to close the latter and form a part of the outer wall. Stud bolts 15 may be used to secure the plate 14 in place.

The auxiliary wall 11 is drilled and threaded as at 16 to receive one end of a hydraulic pump fitting, the fitting comprising a housing 17 having a bore 18 in which a piston 19 is reciprocated to pump hydraulic fluid. The opposite end of the housing 17 is threaded and extends through an

2

opening 20 in the plate 14 so that a nut 21 may be mounted thereon to provide a solid mounting for the hydraulic pumping mechanism. A stuffing nut 22 is preferably provided to insure the piston's being operative in a tight cylinder.

A hydraulic fluid intake port 23 is provided on the housing 17 and leads into the cylinder 18. A ball valve 24 is provided for automatic opening and closing of the intake port 23 as the piston

19 is operated.

An outlet or pressure port 25 is provided from the cylinder and a ball valve 26 is mounted on a suitable seat, as shown, to close the port when the piston is pulled outwardly in the cylinder 18, a spring 27 being provided to bias the ball 26 towards closing the outlet or port 25. The function and operation of the piston and valves 24 and 26 is deemed quite obvious to those skilled in the art, the lever 28 being provided to reciprocate the piston or plunger 19, there being an arm 29 extending from the outer wall of the movable jaw on which a link 30 is pivotally mounted as at 31, the opposite end of the link 30 being slidably and pivotally connected to the outer end of the piston as at 32. The elongated opening in the link to permit the sliding pivot is indicated at 33.

It is deemed apparent that the level of the fluid 7 in the reservoir 6 must be above the level of the ports 23 and 25 for proper operation, and it may readily be seen that the operation of the lever 28 will force fluid under pressure out of the port 25 past the valve 26 and into the passage 12.

To operate my vise jaw hydraulically, I have provided a hollow cylinder 34 in the stem 4 of the movable jaw 5, the cylinder being bored from the outer end of the stem and the bore being closed by a threaded plug 35 after the device is assembled. The under side of the stem 4 is provided with a longitudinal slot 36 through which a bumper or stop 37 extends, the stop 37 being fixed to the base 1, and the slot being of sufficient length to permit the stem to reciprocate the desired distance to open and close the jaw of the vise.

Within the cylinder 34, a bumper piston 38 is carried with one end abutting the stop 37 as shown, the piston being of a length to extend beyond the limits of the slot 36, of course. The opposite end of the piston 38 is provided with a seal 39, held in place, preferably, by a bolt 40 and cap 41, and this seal serves to permit fluid pressure to be built up between the end of the bumper piston 38 and the closed end of the bore 35 so

that said pressure will move the jaw 5 towards the fixed jaw 2.

Pressure is built up in the bore 35 by means of a fluid passage 42 through the stem 4 from the outer end of the bore to and through the inner wall 8 of the jaw 5, as shown, to communicate with the passage 12. Thus, it will be seen that the operation of the lever 28 will move the jaw 5 toward the fixed jaw 2.

I have provided automatic means to open the jaws of my vise. This means comprises a pair of suitable contractile springs 43—43' which are secured between the outer end 44 of the stem 4 and the base 1 to constantly bias the jaws toward open position. It is deemed apparent that when no fluid pressure is present in the bore 35, the springs 43 and 43' will move the jaw 5 away from the jaw 2.

A pressure relief valve operating screw 45 is provided to release the fluid pressure to permit the jaws to open, the relief valve comprising a housing 46 threadedly installed in a manner similar to the installation of the hydraulic pump housing 17, as shown, the housing having a relief port 47 communicating with the channel 12. A needle valve 48 is provided on the inner end of the operating screw 45 for closing and opening the port 47 to allow pressure to leak off of the pressure system and pass back into the fluid reservoir 6 through the outlet ports 49, thus permitting the jaws to open freely. Obviously, a packing nut 50 is provided for the relief valve.

It is deemed apparent that the speed of the opening of the jaws may be controlled by means of the relief valve operating screw 45.

If desired, a second hydraulic pump mechanism, in addition to that already described, and having a smaller diameter piston 51, may be provided on the jaw 5, the second pump being operated in the same manner as the first and having a similar lever and link, not shown, and a supporting arm 52 being provided for said lever and link. The smaller diameter piston will permit greater closing stress to be applied to the jaws, while the larger piston will move the jaws together faster.

Another novel feature of my invention is the provision for closing the jaws of the vise by

means of air pressure. An air valve 53 is mounted on the movable jaw 5 above the fluid level line, and communicates with the reservoir 6 so that a common air pressure line valve may be connected to the valve 53 to force air into the reservoir 6. This air pressure in the reservoir will press against the fluid, obviously, and force same through the ports 23 and 25 to build up pressure in the bore 35 to close the jaws of the vice. For quick operation, the air valve functions admirably, although the closing stress applied to the jaws is limited to the available air pressure. However, the hydraulic pumps may be operated to apply further stress if desired.

An air release valve 54 is provided to relieve the air pressure within the reservoir 6 so that the vise jaws may be moved away from each other.

Having thus described my invention, what I claim is:

As a new article of manufacture a vise consisting of a fixed jaw, a movable jaw, a stem extending from said movable jaw through said fixed jaw, said movable jaw being hollow to provide a fluid reservoir, a hydraulic pump installed in said reservoir below the level of fluid therein, means on said movable jaw for operating said pump, said stem having a bore within same, said bore having its outermost end closed, a bumper piston in said bore, a stop for said piston, said stop being secured to said fixed jaw, said stem having a slot therein adjacent the inner end thereof to receive said stop, and a channel in said stem connecting said pump with the outermost end of said bore for applying fluid pressure between said closed end of said bore and said piston therein to move said movable jaw towards said fixed jaw.
